UNITED STATES PATENT OFFICE

EDWARD E. TREVILLION, OF NEWELLTON, LOUISIANA.

NUT-LOCK.

1,072,275.

Specification of Letters Patent.

Patented Sept. 2, 1913.

Application filed December 28, 1912. Serial No. 739,117.

To all whom it may concern:

Be it known that I, EDWARD E. TREVILLION, a citizen of the United States, residing at Newellton, in the parish of Tensas and 5 State of Louisiana, have invented certain new and useful Improvements in Nut-Locks, of which the following is a specification.

The object of the present invention is to provide a simple and effective form of nut lock which may be easily applied to any 10 size or character of bolt, with the aid of tools ordinarily used.

Heretofore, the common expedient of employing a cotter-pin, which not only requires an expensive operation of drilling a 15 hole, but weakens the construction of the bolt, by so doing, was considered a fairly positive nut lock, but the difficulty lay in the fact that the drilled hole had to be in the 20 proper place, thus necessitating special bolts and sizes, or the desired result was not obtainable.

It is, therefore, my object to provide a locking or wedging member, a portion of 25 which is seated in a groove or notch made adjacent to and parallel with the face of the nut, which member is capable of being quickly or positively applied to any style of bolt, at the proper place, by means of tools 30 carried by a regular mechanic.

In the accompanying drawings, Figure 1 is a view in elevation of a bolt showing the locking member in operative position thereon. Fig. 2 is a vertical sectional view, on 35 the line 2—2 of Fig. 1. Fig. 3 is a top plan view. Fig. 4 is a horizontal sectional view taken on the line 4—4 of Fig. 2. Fig. 5 is a view in elevation, showing more clearly the interlocking groove, the locking member being omitted. Fig. 6 shows a slightly modified 40 form of locking member. Fig. 7 is a detail view of the locking member alone.

Referring to the drawings, the numeral 1 designates a bolt having the threaded end 45 portion 2 upon which is screwed a nut 3. It is to be understood that these parts are common to the structure of every bolt, irrespective of its size, and when the nut has been screwed upon its place tightly against 50 the abutment, I take a hack-saw, thin file, or similar tool, and make a groove or notch 4 in the threaded portion, transversely of the bolt 2, and immediately adjacent, as well as parallel to the face of the nut 3. Into this 55 interlocking groove 4 I place the attenuated or flattened portion 5' of a piece of wire 5,

previously so flattened by a blow of a hammer or the like, the ends of the wire being brought around the bolt, and secured together by twisting with a pair of pliers, as 60 shown at 6. The twisted ends or the knot in the ring binds against the face of the nut at the side of the bolt opposite the groove and it is to be noted that the groove is preferably 65 narrower than the gage of the thread. The enlarged portions of the wire ring 5 at the 70 ends of the groove preclude of this member turning in either direction when once applied. The formation of the groove 4, as before stated, at an angle to the threads, 75 causes the flattened portion of the ring member 5 to act as a wedge against tendency of the nut to unscrew when it has been applied as hereinbefore described, and likelihood of the locking ring following the path 80 of the threads when the nut 3 tends to move off the bolt, is prevented, this action being ordinarily experienced where a ring locking member of similar nature to the present invention is secured around the threaded portion 85 of the bolt without any interlocking connection therewith.

It will be obvious that to provide the bolt with the groove 4 does not injure or in any way destroy its usefulness, nor does it weaken 85 the bolt. The advantages of my construction of nut lock are apparent in that a very effective one is provided, at a minimum expense, and for any size or style of bolt.

In Fig. 6 is illustrated a slightly modified 90 form of locking member 5^a, which is not provided with an attenuated portion, as in the preferred form, but is merely engaged in a similar groove 4, cut in the threaded portion 2 of the bolt 1, adjacent the nut 3 as 95 hereinbefore described with respect to the preferred form. The interlocking action is just as effective in this modified form but the flattening of the ring member increases, in an apparent manner the wedging action of 100 said member. It will, furthermore, be understood that should it become necessary to screw the nut upon the bolt tighter, in such a manner that space would be left between the locking member and the nut, it would 105 only be necessary to pass the wire 5 around the bolt a second time between the first turn which lies in the groove, or as many other turns as might be required to fill the intervening space described. This would prevent the necessity of making a new groove 110 adjacent to the nut and still the lock-

ing action would be just as effective. In tightening the nut, it would even be practicable instead of continuing the wrapping of the wire as just described around the bolt, 5 to allow the locking ring 5 to remain in its position and to fill the intervening space between said ring and the nut by using an additional piece of wire and twisting it tightly.

Having thus described my invention, what 10 I claim as new is:

1. In a nut lock, the combination with a bolt having a threaded portion and a nut adapted to be screwed thereupon, said bolt having a groove in the threaded portion adjacent the nut and formed at right angles to the axis of said bolt, the width of the groove aforesaid being narrower than the gage of the threads on the bolt, of a locking ring member of relatively hard material and 15 of less diameter than the bolt, secured around said bolt and having a portion seated

in the groove whereby to prevent tendency of the ring member to follow the thread on unscrewing movement of the nut.

2. In a nut lock, the combination with a 25 threaded bolt and a nut therefor, the bolt having a groove in its threaded portion adjacent the nut and at right angles to the axis of the bolt, of a locking ring of less diameter than the diameter of the bolt and 30 formed with an attenuated portion adapted to seat in the groove aforesaid the enlarged portions of the ring at the ends of the groove forming wedges to prevent turning of the locking member. 35

In testimony whereof I affix my signature in presence of two witnesses.

EDWARD E. TREVILLION.
